UNITED STATES PATENT OFFICE.

MERTON W. WENTWORTH, OF BATTLE CREEK, MICHIGAN, ASSIGNOR TO SANITARIUM AND HOSPITAL EQUIPMENT COMPANY, A CORPORATION OF MICHIGAN.

THERAPEUTIC APPARATUS.

Application filed July 6, 1925. Serial No. 41,465.

This invention relates to improvements in therapeutic apparatus, and has reference more particularly to a device in the nature of a vibrating table for administering both mechanical and manual massage treatments to patients. In its preferred and most complete form, herein illustrated and hereinafter described, there is also associated with the table an electric cabinet for the administering 10 of heat and light treatments to the patient.

Among the more important objects of the invention are, to provide an improved table for administering mechanical massage treatment, by which rapid vibratory effects may be conveniently applied to the entire body of the patient seated or lying upon the table, to provide, in such a device, improved means for effecting and cushioning the vibrations, 20 to provide a table equipped for the application of mechanical vibration which may also conveniently serve as a rest or support for a patient undergoing manual massage, and to provide, in association with such a table, improved means for applying heat and light treatments either independently or supplemental to the massage treatments. Other objects and many of the attendant advantages of the invention will be apparent to persons familiar with therapeutic devices of this class from the following detailed description, taken in connection with the accompanying drawings wherein I have illustrated one practical and preferred physical embodiment of the principle of the invention and in which—

Fig. 1 is a side elevation of the complete apparatus, viewed from the right of Fig. 2;

Fig. 2 is a vertical section taken on the 40 offset line 2—2 of Fig. 1;

Fig. 3 is a longitudinal section through the top of the table and the cabinet, taken on the offset line 3—3 of Fig. 2;

Fig. 4 is an enlarged axial section through 45 the vibrator and its supporting shaft;

Fig. 5 is an enlarged sectional detail showing the manner of fastening the body walls and end coverings of the cabinet to the end frames of the latter; and

Fig. 6 is an enlarged sectional detail illus-

trating certain structural details of the body of the cabinet.

Referring to the drawings, 10 designates a rectangular base plate, on the four corners of which are securely mounted upstanding coil springs 11. The table comprises vertical corner legs 12, conveniently made of angle bars, side and end bars 13 and 14 rigidly connecting and spacing the upper ends of the legs 12, inclined braces 15 connecting the side bars 13 to the legs 12, and horizontal struts 16 rigidly connecting and spacing the braces 15. To the lower ends of the legs 12 are attached feet 17, each of which is formed with an annular shoulder 18 (Fig. 2) and with a depending mandrel 19 that is spirally grooved to receive the upper ends of the springs 11, whereby the legs of the table are attached to the springs and prevented from becoming displaced from the latter under the vertical vibrating movements of the table as herein-after described. Attached to and supported by the side and end bars 13 and 14 is a flat table top 20.

To effect the vibration of the table, there is mounted on the base 10 an electric motor conventionally illustrated at 21, the shaft of which carries a pulley 22 that is connected by a belt 23 to a pulley 24 (Fig. 4) preferably formed integral with a drum 25. This drum 25 is journaled, preferably by roller bearings 26, on a fixed shaft 27 that extends crosswise of the table frame a short distance beneath the table top 20 and at the longitudinal center of the latter; the ends of said shaft 27 being mounted and keyed in hanger brackets 28 that are attached to the side bars 13. To the ends of the drum 25 are attached sleeves 29 internally grooved to contain packing rings 31 fitted on sleeves 32 encircling and pinned to the shaft 27, whereby grease packed in the drum 25 to lubricate the bearings 26 is confined against substantial leakage. Keyed on the shaft 27 beyond the ends of the sleeves 29 and encircling the latter are cups 33 designed to catch any drippings of grease or oil that may work past the packing rings 31.

On, and preferably integral with, the 100

drum 25 is a radially extending lug 34, the weight of which serves to unbalance the drum 25 and, as the drum is rapidly rotated by the motor, to impart a fine, rapid vibration to the shaft 27 which is transmitted through the rigid hanger brackets 28 to the sides of the table frame.

The device as thus far described is complete for purposes of administering mechanical vibration and manual massage treatment to a patient seated or lying on the table top. To enhance the therapeutic efficiency of the apparatus, however, I preferably, and as herein shown, equip the table with an electric cabinet by which light and heat treatment may be administered either independently or as supplemental to the vibration and massage treatment. Describing this cabinet, in its general features it comprises a substantially semi-cylindrical hood hinged at one edge to one of the side rails 13 of the table frame and of a width to substantially span and cover the table top. If desired to administer light and heat treatment to the entire body of a patient it may be made in a length substantially equal to that of the table; but I have herein shown the cabinet as somewhat shorter and equipped at its ends with split curtains, so that the head and feet of the patient may be outside the cabinet, while his trunk is being subjected to the heat and light effects within the latter. Describing the cabinet more in detail, 35 designates each of a pair of semi-obleng metal end frames, each of which is formed on its inner side and slightly inwardly of its outer edge, with a rib or flange 36 (Fig. 5). The vertical limbs of the frame 35 are connected and spaced at their lower ends by wooden bars 37 (Fig. 6). The body or shell of the cabinet is preferably formed as a laminated structure, and comprises, in the instance shown, an inner sheet 38 of aluminum, which is attached by screws 39 (Fig. 5) to the inner side of the flange 36, a covering 41 comprising one or more sheets of asbestos paper overlying the aluminum sheet 38, a thin dead air space 42 (Fig. 3) outside the asbestos covering 41, for insulation purposes and to accommodate the light wires hereinafter described, next a thin sheet of steel 43, and over the latter an outer covering 44 of imitation leather. The steel sheet 43 and the leather covering 44 are attached to the outer side of the flange 36 by bands 45 and screws 46 (Fig. 5).

Attached to the inner sides of the end frames 35, by suitable fastenings indicated at 47 (Fig. 5) are curtains 48 that, as shown in Fig. 2, are centrally split for all or the major portion of their height, as shown at 49, so as to permit the passage of the head and feet of a patient between them. The inner aluminum lamination 38 overlies the inner sides of the side bars 37, as shown in Fig.

6, the asbestos layer 41 terminates at the upper edges of the bars 37, and the steel and leather layers 43 and 44 overlie the outer sides of the bars 37; and the several layers are bound to the bottom edges of the bars 37 by channel-shaped binding strips 51 and fastening screws 52 (Fig. 6).

The cabinet casing is interiorly equipped with electric lights to furnish heat and the therapeutic light rays, such as the infra red rays. To the inner lamination 38, on each longitudinal half of the casing are attached, by bolts 53, clamp brackets 54 which embrace the sockets 55 of lamp bulbs 56. Current is supplied to the lamps through circuit wires 57 led into the casing through an insulation sleeve 58 mounted in the roof of the casing, the wires being disposed in the dead air space 42 (Figs. 2 and 3).

The cabinet casing is hinged preferably by the means shown in Figs. 1 and 2. Bolted to the outer sides of the side rails 13 are a plurality of U-shaped brackets 59, in which is mounted a stop rod 61 disposed adjacent to and opposite the outer sides of the rails 13, and in the upper free ends of which is also mounted a hinge rod 62. Attached to one lower margin of the casing by bolts 63 are a pair of downwardly turned hinges 64 that are slidably mounted on the rod 62 and include depending extensions or tail pieces 65, that, when the casing is swung backwardly to fully uncover the table top 20, strike the stop rod 61 and thus hold the casing in fully opened position. To the front side of the casing are attached a pair of handles 66 to facilitate the manual opening and closing of the casing.

The manner in which the appliance serves the stated purposes and objects thereof will be readily apparent from the foregoing description of its structural features. The cabinet having been swung back, the patient takes his position on the table top, and the motor 21 is put in operation. The rapid rotation of the drum 25 carrying the eccentric weight 34 imparts a rapid vibratory movement to the table top 20, the vibrations being transmitted to any portion of the body of the patient requiring vibratory treatment by causing the patient to so dispose himself that that portion of his body will lie in contact with the table. In such position the patient is also favorably situated for the application of manual or mechanical massage. Where, in addition to, or in lieu of, the vibratory treatment, heat and light treatment is to be applied, the cabinet is lowered to enclose the part of the body of the patient requiring such treatment, and the lights are turned on. By hinging the cabinet so that it is slidable on the hinge rod lengthwise of the table, light and heat may be applied to the upper or lower part of the body of a patient lying on the table;

without requiring the patient to shift his position. Manifestly, the light and heat treatment may be applied either independently or simultaneously with the vibratory treatment.

While I have herein shown and described one practical physical embodiment of the principle of the invention which satisfactorily fulfills stated purposes and objects thereof, it is manifest that many of the structural details, including the means for effecting the vibratory movements, may be variously modified without departing from the substance of the invention or sacrificing any of the advantages thereof. For instance, rubber balls might be substituted for the table supporting springs 11. Hence, I reserve all such variations, modifications and mechanical equivalents as fall within the spirit and purview of the appended claims.

I claim—

1. In a therapeutic apparatus of the character described, the combination of a table, springs sustaining the weight of said table, a shaft mounted on said table beneath the table top, a drum on said shaft, an eccentric weight on said drum, a motor, and driving connections from said motor to said drum for rotating the latter at high speed.

2. In a therapeutic apparatus of the character described, the combination of a table, springs sustaining the weight of said table, a fixed shaft mounted on said table, a drum journaled on said shaft, an eccentric weight on said drum, an electric motor beneath said table, and driving connections from said motor to said drum for rotating the latter at high speed.

3. In a therapeutic apparatus of the character described, the combination of a table, a base for supporting said table, springs mounted on said base on which the legs of said table are stepped, a fixed shaft mounted on said table beneath the table top, a drum journaled by anti-friction bearings on said shaft, an eccentric weight on said drum, an electric motor mounted on said base, and a pulley and belt drive from said motor to said drum.

4. In a therapeutic apparatus of the character described, the combination with a vibratable massage table, of an electric cabinet hinged to said table and formed with an open side in register with the table top when said cabinet is in operating position.

5. In a therapeutic apparatus of the character described, the combination with a vibratable massage table having a flat top, of an electric cabinet comprising a substantially semi-cylindrical body or shell, and openable end closures therefor, and means for hingedly attaching said cabinet at one edge of said body or shell to an edge of the table.

6. In a therapeutic apparatus of the char-

acter described, the combination with a vibratable massage table having a flat top, of an electric cabinet, comprising end frames, a substantially semi-cylindrical body or shell connecting said end frames, and curtains closing said end frames, and means for hingedly attaching said cabinet at one edge of said body or shell to an edge of the table.

7. In a therapeutic apparatus of the character described, the combination with a vibratable massage table, of an electric cabinet hinged at one edge to an edge of said table and formed with an open side adapted to register with the table top when said cabinet is in operating position, and cooperating stop devices limiting the opening movement of said cabinet.

8. In a therapeutic apparatus of the character described, the combination with a table, of an electric cabinet hinged to said table with capacity of movement on the latter in a direction parallel with the axis of the hinge.

9. In a therapeutic apparatus of the character described, the combination with a table, of a hinge rod mounted on said table parallel with one edge of the latter, an electric cabinet, and hinge members attached to said cabinet and slideable on said hinge rod.

10. In a therapeutic apparatus of the character described, the combination with a structure adapted to support the body of a patient, of mechanical means for imparting vibrating movement to said structure, and means mounted on said structure for administering heat and light treatments to a patient on said structure.

11. In a therapeutic apparatus of the character described, the combination with a massage table, of resilient means sustaining the weight of said table, mechanical means for imparting vibrating movement to said table, and an electric cabinet mounted on said table for administering heat and light treatments to a patient on said table.

12. In a therapeutic apparatus of the character described, the combination with a vibratable massage table, of an electric cabinet hinged to swing over said table to and from operative position and formed with an open side in register with the top of the table when said cabinet is in operative position.

13. In a therapeutic apparatus of the character described, the combination of a vibratable structure, a shaft carried by said structure, a drum on said shaft, an eccentric weight on said drum, a motor, and driving connections from said motor to said drum for rotating the latter at high speed.

14. In a therapeutic apparatus of the character described, the combination of a vibratable structure, a shaft carried by said structure, a drum journaled by anti-friction bearings on said shaft, an eccentric

weight on said drum, a motor, and driving connections from said motor to said drum for rotating the latter at high speed.

15. In a therapeutic apparatus of the character described, the combination of a vibratable structure, a shaft carried by said structure, a drum journaled by a pair of spaced anti-friction bearings on said shaft and provided with a hollow portion between said bear-

ings adapted to contain a lubricant, an eccentric weight on said drum, a pair of guards one at either end of said drum for receiving any lubricant which may be discharged from the ends of the drum, and means for rotating said drum at high speed. 15

In witness of the foregoing I affix my signature.

MERTON W. WENTWORTH.
